Kawata et al., entitled, "OVEN," U.S. Appl. No. 29/253,285, filed Feb. 3, 2006, pending.

Mizuno, entitled, "OVEN," U.S. Appl. No. 29/262,695, filed Jul. 10, 2006, pending.

Primary Examiner—Ruth McInroy(74) *Attorney, Agent, or Firm*—Nixon & Vanderhye, PC(57) **CLAIM**

The ornamental design for a "microwave oven," as shown and described.

DESCRIPTION

FIG. 1 is a right side, top, front perspective view of an microwave oven in accordance with my new design;

FIG. 2 is a front elevational view thereof;

FIG. 3 is a rear elevational view thereof; and

FIG. 4 is a top plan view thereof;

FIG. 5 is a bottom plan view thereof;

FIG. 6 is a right side elevational view thereof; and,

FIG. 7 is a left side elevational view thereof.
